UNITED STATES PATENT OFFICE

115,779

DESIGN FOR A WOODWORKING MACHINE

William B. Boice, Toledo, Ohio

Application December 7, 1938, Serial No. 81,613

Term of patent 7 years

To all whom it may concern:

Be it known that I, William B. Boice, a citizen of the United States, residing in Toledo, in the county of Lucas and State of Ohio, have invented a new, original, and ornamental Design for a Woodworking Machine, of which the following is a specification, reference being had to the accompanying drawings, forming a part thereof and in which:

Figure 1 is a front elevational view of a woodworking machine embodying my new design.

Figure 2 is a side elevational view of Fig. 1 looking at said figure from the right.

Figure 3 is a side elevational view of Fig. 1 looking at said figure from the left.

The top of the woodworking machine is substantially conventional.

I claim:

The ornamental design for a woodworking machine, as described and shown.

WILLIAM B. BOICE.
